[57] CLAIM

The ornamental design for a printer feeder for plastic
lids, as shown.

DESCRIPTION

FIG. 1 is a perspective view of the printer feeder for
plastic lids showing my new design;

FIG. 2 is a perspective view taken from the side oppo-
site to FIG. 1;

FIG. 3 is a side elevational view;

FIG. 4 is a side elevational view of the side opposite to
that shown in FIG. 3; and

FIG. 5 is a top plan view thereof.

Fig. 1.
